US00D998751S

(12) **United States Design Patent** (10) **Patent No.:** **US D998,751 S**
(45) **Date of Patent:** **** Sep. 12, 2023**

(54) **WATER PURIFIER**

(71) Applicant: **GUANGDONG XINBAO ELECTRICAL APPLIANCES HOLDINGS CO., LTD.**, Guangdong (CN)

(72) Inventors: **Jiangang Guo**, Foshan (CN); **Xiaojian Qian**, Foshan (CN); **Yikui Yu**, Foshan (CN)

(73) Assignee: **GUANGDONG XINBAO ELECTRICAL APPLIANCES HOLDINGS CO., LTD.**

(**) Term: **15 Years**

(21) Appl. No.: **29/733,962**

(22) Filed: **May 7, 2020**

(51) LOC (14) Cl. **23-01**

(52) U.S. Cl.

USPC **D23/207**

Primary Examiner — Jennifer Rivard

Assistant Examiner — Jonathan E Fiencke

(57) **CLAIM**

The ornamental design for a water purifier, as shown and described.

DESCRIPTION

FIG. 1 is a front view of a water purifier, showing our new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines and areas within depict portions of the water purifier that form no part of the claimed design.

1 Claim, 7 Drawing Sheets
